NORMAN H. BEEBE, OF DAVENPORT, IOWA, ASSIGNOR TO LEE BROOM & DUSTER COMPANY, OF LINCOLN, NEBRASKA, A CORPORATION OF IOWA.

BROOM-CLAMPING MACHINE.

1,252,992.

Specification of Letters Patent.

Patented Jan. 8, 1918.

Application filed February 26, 1915. Serial No. 10,758.

To all whom it may concern:

Be it known that I, NORMAN H. BEEBE, a citizen of the United States, residing at Davenport, in the county of Scott and State 5 of Iowa, have invented certain new and useful Improvements in Broom-Clamping Machines, of which the following is a specification.

My invention relates to an improvement 10 in broom clamping machines, and more particularly to that class of machines used to fasten the clamps or jaws of metal clamp brooms. This machine compresses the fiber, locks the clamping members together at the 15 broom corners, and attaches the handle to the clamps by forming a ring about their centrally extended, annularly grooved portions.

In the accompanying drawings:—

20 Figure 1 is a front elevation of clamping portion of the machine, showing the various parts in the position they occupy when ready to begin the clamping operation;

25 Fig. 2 is a front elevation of the mechanism shown in Fig. 1, with the parts in the position they occupy while clamping a broom;

Fig. 3 is a side view of Fig. 1;

30 Fig. 4 shows in perspective the bell-crank used to operate the lip-straightener;

Fig. 5 is a view in perspective of one of the oscillating clamping fingers and finger-blocks;

35 Fig. 6 shows in perspective, fragments of the main frame, lower pressure-head, clamp forms, ring-anvil, and the complete finger-block;

Fig. 7 is a fragmentary view of a pair of broom clamps; and

40 Figs. 8 and 9 are horizontal sections taken through the upper and lower mechanism respectively.

Fig. 10, is a skeleton perspective view of the cams, heads, plungers, and operating 45 connections therebetween.

Fig. 11, is a transverse vertical section through the heads and plungers and associating mechanism.

Number 1 is the main frame. Numbers 50 2, 3, 4 and 5 are V-guides attached to the face or front of main frame 1, by bolts, some of which are shown by numbers 6, 7, 8 and 9.

The upper crosshead 10 is slidably held between the guides 2 and 3.

55 The lower crosshead 11 is slidably held

between the guides 4 and 5. A clamp form 12 is attached to the lower end of crosshead 10. A similar form 13 is attached to the lower pressure-head 14. The lower pressure-head 14 is clamped to the front of main 60 frame 1, by bolts 15 and 16. These bolts pass through slotted holes 15' and 16' respectively, as shown, thus allowing vertical adjustment of pressure-head 14. The lower end of head 14 rests on a wedge-block 17, 65 also shown in dotted lines, Fig. 3. The wedge-block 17 rests on the shelf 18, which shelf is a part of frame 1. The block 17 is held in place by bolts 19 and 20.

The anvil 21 upon which the ring rests is 70 attached to form 13 and head 14 by bolts 22 and 23. These bolts pass through a slot 23' in the anvil, so that the anvil may be adjusted. The anvil rests on a projection 25 of the head 14 and secured to the lower portion of the anvil are two spring-staple holders 24—24. Finger-blocks 26 and 27 are located at either side of head 14. These blocks are provided with a round extension 28, Fig. 6. The extension, as will be seen, 80 is reduced in size and threaded to receive a nut on its outer end. The blocks are provided with slots 26', through which the bolts 29 and 30 pass. These bolts are screwed into the main frame 1. 85

The pressure-head 14 is provided with a T-slot 31, Fig. 6. The head not shown of the bolt 32 is inserted in slot 31. This bolt passes through a hole in block 26, thus providing means of clamping the block against 90 the head 14. It will be noted this block is adjustably attached to the main frame with means provided for clamping to head 14, so that the head and block may be adjusted in unison, or independently. 95

The oscillating fingers 33 and 34 pivot about the extensions 28. The bell cranks 35 and 36 are pivoted at 35' and 36' respectively within the fingers 33 and 34. Clamp end straighteners 37 and 38 are pivotally 100 secured within the slotted extensions 39 and 40 of the upper crosshead 10. The straighteners are provided with adjusting screws 41 and 42. These screws pass through holes in the spring clips 43 and 44. Coil springs 45 and 46 are attached to clips 43 and 44 respectively at one of their ends, and to the head 10 at their opposite ends. These springs serve to hold the adjusting screws 41 and 42 against the head 10. 110

Plungers 47 and 48 are adjustably attached to lower sliding head 11, by the bolts 49, 50, 51 and 52. The upper ends of the plungers are provided with rollers 53 and 54. These rollers are in contact with the fingers 33 and 34.

The plungers are so formed as to provide a shelf, into which are screwed the plunger screws 55 and 56. These screws come in contact with the bell cranks 35 and 36, during the clenching operation, see Fig. 2.

For the purpose of forming the staple 57 (as shown in Fig. 1) into the ring 58 (as shown in Fig. 7) the plunger 59 is employed. 15 This plunger slides in a groove in the head 10. The adjustable plate 60 is attached to head 10 by means of the screws 61, 62, 63 and 64. This plate holds the plunger 59 in the groove, and at its lower end fits about 20 the neck or central curved portion of the clamp. By means of the screws 65 and 66 the plate 60 is adjustable, and will resist a heavy strain without slipping. During the compressing and clenching operations, the 25 rollers 67 and 68, carried by the upper cross-head 10, assist the rollers 53 and 54 in holding the fingers 33 and 34 in place against the side pressure of the fiber, see Fig. 2.

The rod 69 is adjustable for length, and 30 serves to assist the head 14 in resisting the pressure.

Numbers 70 and 71 are the broom clamps, see Fig. 7.

The movement of the lower head 11 is 35 effected by a cam 81 mounted upon the cam shaft 82. This cam is adapted to actuate parallel beams 83, the inner ends of which are connected to the main frame while the outer free ends are connected by a tie rod 40 84 to an oscillating arm 85 affixed to a rock arm 86 suitably journaled in the main frame. Secured to the outer free end of the rock shaft 86 is a rock arm or tappet 87 which is 45 adapted to impart a reciprocating movement to the lower head 11 through the medium of the roller 88. The movement of the upper head 10 and plunger 59 are controlled by cams 89 and 90 respectively which are also mounted on the cam shaft 82.

50 The operations of the machine are as follows:—The staple is first placed in the semi-annular groove 75 in anvil 21 with its two ends extending upward in the notches 76 of the staple-holder 24, see Figs. 1 and 6.

55 A clamp 71 is now placed in the form 13. The clamp 70 is then placed in form 12. The operator places a quantity of fiber over the lower clamp, as shown in Fig. 3. The handle 72 is inserted between the fibers, with the 60 annular groove 77 of the handle 72 in line with the annular beads 78 of the clamps. The head 11 moves upward just far enough to cause the rollers 53 and 54 to raise the fingers to the vertical position, shown in 65 Fig. 2. Head 11 now remains stationary and

head 10 descends from the position shown in Fig. 1 to that shown in Fig. 2. In this position the hook ends 79 and 80 of the clamps just pass each other. Head 10 now remains stationary and head 11 moves upward. The screws 55 and 56 come in contact with bell cranks 35 and 36, imparting motion to them. These bell-cranks in turn impart motion to the straighteners 37 and 38. The straighteners force the clamp-ends 75 to a straight line, as shown in Fig. 7.

During the time of the latter operations, the plunger 59 has descended, curving the staple into the form of a ring 58, in the beads 78 of the clamps, see Fig. 7. Just as 80 the hook ends 79 and 80 of the clamps are brought to a straight line, the head 10 rises. The pressure of the fiber forces the clamps apart, thus causing the hook ends 79 and 80 to hook into each other, as shown in 85 Fig. 7.

The lower head now descends, and the machine is ready to repeat its cycle of operations.

I claim:—

1. A broom-clamping machine comprising movable upper and lower cross-heads, a clamp-form carried by one of said cross-heads, a stationary clamp-form, said clamp forms adapted to receive clamps therewith, said clamps having hook ends and having centrally-extended annularly-grooved or beaded portions, means carried by the upper cross-head and stationary clamp-form for automatically forcing said 100 hook ends into the path of each other when pressure is applied by the lower cross-head to bring the clamps together around the fibers of the broom, said hook ends hooking together or interlocking as a result of the 105 expansive outward pressure of the fibers when the external pressure upon the clamps is removed, and means for bending a staple into the form of a ring in the groove or bead of the centrally-extended portions of the 110 clamps.

2. A broom-making machine comprising movable cross-heads, a clamp-form carried by one of said cross-heads, a clamp-form co-operating therewith, said clamp-forms 115 adapted to hold broom-clamps, an anvil and staple-holders carried thereby to receive a staple, and means carried by one cross-head to bend the staple into a ring around a portion of the clamps during the broom-clamping operation.

3. A broom-clamping machine comprising two movable cross-heads, a clamp-form carried by one of said cross-heads, a clamp-form co-operating therewith, said forms 125 adapted to receive clamps, fingers pivoted to and carried by the frame, clamp end-straighteners pivoted to and carried by one cross-head, bell-cranks carried by the fingers, and means carried by the other cross- 130

head in position to engage the bell-cranks to cause the latter to exert lateral pressure upon the clamp end straighteners to force the clamp ends into position to hook or interlock with each other.

4. A broom-clamping machine comprising two movable cross-heads, a clamp-form carried by one of said cross-heads, a clamp-form coöperating therewith, said forms adapted to receive clamps, fingers pivoted to and carried by the frame, clamp end straighteners pivoted to and carried by one cross-head, springs attached to the straighteners and to the cross-head for swinging the straighteners in one direction, adjustable screws connected with the straighteners and bearing against the head, bell-cranks carried by the fingers, and adjustable means carried by the other cross-head in position to engage the bell-cranks to cause the latter to exert lateral pressure upon the clamp end straighteners to force the clamp ends into position to hook or interlock with each other.

5. A broom-clamping machine comprising two movable cross-heads, a clamp-form carried by one of said cross-heads, a clamp-form coöperating therewith, said clamp forms adapted to receive clamps, fingers pivotally mounted on and carried by the frame, clamp end straighteners pivotally carried by and mounted on one cross-head, bell-crank levers pivotally mounted in the fingers, plungers carried by the other cross-head, said plungers having rollers in position to engage and swing the fingers into position, and rollers carried by the first mentioned cross-head for engaging and supporting said fingers.

6. A broom-clamping machine comprising two movable cross-heads, a clamp-form carried by one of said cross-heads, a clamp-form coöperating therewith, said clamp forms adapted to receive clamps, fingers pivotally mounted on and carried by the frame, clamp end straighteners pivotally carried by and mounted on one cross-head, bell-crank levers pivotally mounted in the fingers, plungers carried by one cross-head, said plungers having rollers in position to engage and swing the fingers into position, rollers carried by the other cross-head for engaging and supporting said fingers, and means on one cross-head for engaging the bell-crank levers to cause them to exert lateral pressure upon the clamp end straighteners.

7. A broom-clamping machine comprising two movable cross-heads, a clamp-form carried by one of said cross-heads, a clamp-form coöperating therewith, clamps adapted to be carried by the forms, fingers pivotally mounted on and carried by the frame, clamp end straighteners pivotally carried by and mounted on one cross-head, bell-crank levers pivotally mounted in the fingers, plungers

carried by one cross-head, said plungers having rollers in position to engage and swing the fingers into position, rollers carried by the other cross-head for engaging and supporting said fingers, means on one cross-head for engaging the bell-crank levers to cause them to exert lateral pressure upon the clamp end straighteners, an anvil and spring-staple holders to receive and hold the staple, and a plunger movable with respect to the first mentioned cross-head for engaging the ends of the staple and bending the staple into a ring around a portion of the clamp.

8. A broom-clamping machine comprising two movable cross-heads, a clamp-form carried by one of said cross-heads, a clamp-form coöperating therewith, said clamp forms adapted to receive clamps, fingers pivotally mounted on and carried by the frame, clamp end straighteners pivotally carried by and mounted on one cross-head, bell-crank levers pivotally mounted in the fingers, plungers carried by the other cross-head, said plungers having rollers in position to engage and swing the fingers into position, rollers carried by the first mentioned cross-head for engaging and supporting said fingers, means on one cross-head for engaging the bell-crank levers to cause them to exert lateral pressure upon the clamp end straighteners, an anvil and spring-staple holders to receive and hold the staple, a plunger movable with respect to the first mentioned cross-head for engaging the ends of the staple and bending the staple into a ring around a portion of the clamp, a plate for holding the plunger in place, and screws in position to engage and adjust said plate and resist heavy strain thereupon without slipping.

9. A broom-clamping machine comprising a main frame, movable cross-heads, a pressure-head adjustably connected to the frame, a clamp-form attached thereto, a stationary clamp-form, fingers pivotally and adjustably mounted on the frame, clamp end straighteners pivotally connected with one cross-head, means carried by the fingers for exerting pressure upon the straighteners, adjustable means carried by one of the cross-heads for engaging said means carried by the fingers, plungers connected with one cross-head and carrying rollers, and the other cross-head having rollers, said rollers adapted to engage and hold the fingers in position while the means carried by the fingers are forced against the straighteners.

10. A broom-clamping machine comprising a frame, movable cross-heads, a pressure-head adjustably connected to the main frame, a wedge-block resting on a shelf on the main frame upon which another pressure-head rests, means for holding said wedge-block in place, fingers pivotally

mounted on and carried by the frame, bell-crank levers pivotally connected with the fingers, plungers carried by the cross-head and having rollers in position to engage and move the fingers laterally, and adjustable means carried by the plungers in position to engage the bell-crank levers to swing them upon their pivots.

11. A broom-clamping machine comprising a frame, movable cross-heads, a clamp-form carried by one cross-head, a pressure-head adjustably connected to the main frame, a clamp-form attached to the pressure-head, a projection on the pressure-head, a staple holder secured to the projection, an anvil adjustably attached to the pressure-head and adjacent clamp-form, and an adjustable rod forming a support for the outer end of the pressure-head projection.

12. A broom-clamping machine comprising a frame, two movable cross-heads, a clamp form carried by one cross-head, a pressure head adjustably connected to the

main frame, a clamp-form attached to the pressure-head, means for adjustably supporting the latter, finger-blocks adjustably supported on either side of the pressure-head, the pressure-head provided with T-slots, bolts extending through finger-blocks with their heads in the T-slots of the pressure-head, the finger-blocks having round extensions, fingers pivotally mounted on these extensions, bell-crank levers pivotally mounted in the fingers, plungers carried by the lower movable cross-head and having rollers in position to engage and raise the fingers and adjustable means for engaging the bell-crank levers to cause the latter to move inwardly and exert pressure.

In testimony whereof I affix my signature, in the presence of two witnesses.

NORMAN H. BEEBE.
